UNITED STATES PATENT OFFICE.

EDWARD C. MEISSNER, OF ST. LOUIS, MISSOURI, ASSIGNOR, BY MESNE ASSIGNMENTS, TO CHICAGO PNEUMATIC TOOL COMPANY, A CORPORATION OF NEW JERSEY.

PNEUMATIC HAMMER.

No. 822,146.

Specification of Letters Patent.

Patented May 29, 1906.

Application filed November 12, 1900. Serial No. 36,212.

To all whom it may concern:

Be it known that I, EDWARD C. MEISSNER, a citizen of the United States, and a resident of the city of St. Louis and State of Missouri, have invented certain new and useful Improvements in Pneumatic Hammers, of which the following is a specification.

My invention relates to what are commonly known as "pneumatic" hammers; and the object thereof is to produce a hammer of this character having novel and advantageous features of construction and operation which will be apparent from the description hereinafter given.

Chief among the advantages of my hammer may be mentioned, first, a novel and efficient valve and valve movement; second, the provision of a supplemental exhaust; and, third, the provision of means for cushioning the rearward stroke of the piston or plunger.

In the present instance I have shown my invention embodied in what is designated a "long-stroke" or "riveting" hammer, in which the piston has a length of stroke greater than its own length and in which my invention finds useful application; but my invention is not limited to this species of hammer.

In the accompanying drawings, which form part of this specification, and wherein like symbols refer to like parts wherever they occur, Figure 1 is a central longitudinal section of my device, showing the valve in its rearmost or open position. Fig. 2 is a similar view showing the valve in its foremost or closed position. Fig. 3 is a cross-sectional view on the dotted line 3 3 of Fig. 1. Fig. 4 is a cross-sectional view on the line 4 4 of Fig. 1. Fig. 5 is a cross-sectional view on the line 5 5 of Fig. 1. Fig. 6 is a cross-sectional view on the line 6 6 of Fig. 1. Fig. 7 is a cross-sectional view on the line 7 7 of Fig. 1. Fig. 8 is a cross-sectional view on the line 8 8 of Fig. 1. Fig. 9 is a detail side view showing the device for preventing the unlocking of the threaded collar. Fig. 10 is a sectional detail view of the valve-bushing. Fig. 11 is a sectional detail view of the valve. Fig. 12 is an enlarged longitudinal section of the upper end of the hammer with the parts in the positions shown in Fig. 1; and Fig. 13, a section of the intermediate portion of the cylinder or barrel, illustrating a modified

form of construction as to the supplemental exhaust, in which the exhaust passes to the atmosphere directly or transversely through a wall of the cylinder.

The principal elements of my construction are a handle, a valve-bushing 2, Fig. 10, enclosed in said handle, a valve 3, Fig. 11, in said bushing, a barrel or cylinder 4, clamped to said handle in alinement therewith, Figs. 1, 2, and 12, and a piston 5 in said cylinder.

The motive fluid employed will for convenience be referred to as "compressed air."

The handle comprises a grasping portion and a cylindrical portion having a cylindrical socket extending nearly the full length thereof, Fig. 12. The purpose of this socket is to contain the valve and valve-bushing; but for reasons of economy and convenience of manufacture it is preferable to fit a separate cylindrical sleeve or socket piece 1 in the socket of the handle rather than mount the valve-bushing directly in the handle-socket itself. This socket-piece 1 is, in effect, a part of the handle and constitutes a valve-block. The bushing 2 fits in the rear end of the socket, and the end of the barrel or cylinder 4 is reduced to fit into the fore end of said socket-piece and abut against the end of the bushing, the bore at the fore end of said socket-piece being enlarged to accommodate said reduced end of the cylinder. The outer surface of said cylindrical portion of the handle is threaded to allow a threaded sleeve 6 to work thereon, and the front end of said sleeve has an inwardly-extending flange 7, which overlaps and engages a shoulder 8, formed on the cylinder in position to abut against the end of the handle. The rear end of said sleeve is provided with ratchet-teeth 9, Fig. 9, and a spring-pressed bolt 10, provided with ratchet-teeth 11 in its end, is mounted on the handle in position to engage the teeth on said collar, and thereby lock said collar against rotation.

The valve-bushing 2 is a cylindrical sleeve fitting tightly in the socket-piece of the handle, and the valve 3 is a cylindrical piece fitting in said bushing and movable endwise therein. The valve-bushing has holes extending through the side thereof and located as follows, Figs. 10 and 12: One of said holes 12 is located back of the rearmost position of the valve, and the other holes 13, 14, 15, 16, 17,

and 18 are opposite the valve in its advanced position. All of these holes in the bushing open on the outside into passage-ways in the socket-piece or valve-block, which communicate, respectively, with the air-supply duct, the atmosphere, and the interior of the barrel or cylinder, Fig. 12. The admission-port 13 or port leading to the air-supply duct 19 is the foremost of the holes in the bushing 5 and is so located as to be covered by the valve in its forward position, Fig. 2, and uncovered when the valve is in its rearward position, Fig. 12. Back of the admission-port 13 are three ports 15, 16, and 17, the foremost, 15, of which communicates with a passage-way 20, extending longitudinally through the wall of the valve-block and the wall of the cylinder, and terminating in a port 21 in the forward end of the cylinder. The rearmost, 17, of said three ports communicates with a passage-way 22, extending longitudinally through the wall of the valve-block and the wall of the cylinder and terminating in a port 23, formed in a circumferential groove 25 in the cylinder, near the rear end thereof. The middle port 16 of said three communicates with the atmosphere through a passage-way 24 in the valve-block and handle and constitutes the main exhaust-port of the device. Two grooves 25 26 are formed in the valve 3 in position to register alternately with the exhaust-port 16. The front groove 25 registers at all times with the foremost, 15, of said three ports, and the rear groove 26 registers with the rearmost, 17, of said three ports at all times. By this construction the front end of the cylinder is vented or exhausted through the port 21, passage-way 20, port 15, groove 25, and the main exhaust-port 16 and passage-way 24, when the valve 40 is in its rearward position, Figs. 1 and 12, admitting live air to the rear of said cylinder, and when the valve is in its forward position, Fig. 2, the rear portion of the cylinder is open 45 to the atmosphere through port 23, passage-way 22, port 17, groove 26, main exhaust-port 16, and passage-way 24.

In order to effect the movement of the valve 3, an annular rib 27 is formed on the 50 rear end thereof, Fig. 11, whereby the cross-sectional area of the rear end exceeds that of the front end. In other words, the valve is of the differential type, whose larger pressure area in the present instance faces 55 rearwardly and whose smaller pressure area faces forwardly. The bore of the bushing is enlarged at the rear end to form a chamber or space to accommodate said rib, Fig. 10, and the shoulder 28 thus formed in said bushing limits the forward movement of the valve. The rearward movement of said valve is limited by a hollow or concaved plug or cap 29 in the end of said bushing and having a flange extending over the end thereof. 65 The outer front edge of this cap is recessed,

and notches or holes 30 are formed in said end and lie opposite the rearmost port 12 in the bushing. From this port 12 a passage-way 31 extends through the handle and the wall of the cylinder to a port 32 in the middle portion of the cylinder between the ports 21 to 23, hereinbefore mentioned. In the operation of the device as soon as the piston or plunger 5 in its forward movement uncovers the intermediate port 32 air from the cylinder flows through said port 32, passage-way 31, and port 12 into the space in the rear of the valve 3 and exerts pressure upon the rear end of said valve. Both ends of the valve are thus submitted to pressure from the same source; but the pressure on the rear end of the valve exceeds that on the front end by reason of the area of the rear end being the larger. Consequently the valve moves forward to the position illustrated in Fig. 2 and 80 shuts off the admission of air into the rear end of the cylinder. A vent-hole 33, formed through the handle and the bushing at the shoulder thereof, permits the admission and escape of air in front of the rib 27 on said valve, and thus keeps the pressure thereon constant.

The return of the plunger is effected by live air admitted into the front end of the cylinder, it being understood that the shank 95 of a tool or button set 34 fits therein tight enough to secure a sufficient pressure. This live air enters the front end of said cylinder through the duct or passage-way 20, which communicates with the port 15 of the bushing in front of the main exhaust-port 16. For this purpose a small port 14, Fig. 10, communicating with the main air-duct 19 is formed in the bushing 2 back of the main admission-port 13 in position to register with 100 the first groove 25 of the valve in the forward position thereof and in position to be closed by the end portion of said valve in the rearward position thereof. By this arrangement as soon as the valve is moved forwardly 105 to close the main admission-port 13 to the rear end of the cylinder and bring its front groove 25 into register with the small port 14 of the supply-duct, Fig. 2, live air enters the front end of the cylinder through the small 110 duct 14, front groove 25 of the valve, port 15, passage-way 20, and port 21. As the rear end of the cylinder is open to the atmosphere while the valve is in its forward position, the air admitted through the small duct 14 into 115 the front end of the cylinder forces the piston rearwardly. In order to prevent the accidental return of the valve to its rearward position, the small duct 14 is bored at such an angle as to cause the air flowing therethrough 120 to impinge against the front wall of the front groove of the valve, whereby the pressure on said front wall is greater than the pressure on the rear wall.

In addition to the exhaust through the 130

valve the device is provided with a supplemental exhaust-port 55, located in the side of the cylinder near the front end thereof, but far enough back to be passed and uncovered by the piston in its forward stroke. The 5 passage-way 56 of this port is always open to the atmosphere. This passage-way may lead directly through the wall of the cylinder, as illustrated in Fig. 13; but it is preferable to have it extend longitudinally through the 10 wall thereof and through the handle, as in Figs. 1, 2, and 12, so that the expelled air will not interfere with the work. As clearly 15 illustrated in Figs. 1 and 2, taken in connection with Figs. 4, 5, and 6, a supplemental exhaust - passage 56 extends from its port 55 rearwardly through the body or wall of the barrel or cylinder, through the reduced rearward end of such cylinder, Fig. 4, through 20 a portion of the cylindrical socket piece or bushing 1, and then emerges on the inner wall of said socket piece or bushing in position to register with the circumferential groove 16, which is in constant communication with the 25 main or regular exhaust-port and passage 24, as clearly illustrated in Fig. 6. Obviously the outlet end of passage 56 may be differently positioned for communicating with the outer air, if desired. The functions of this supplemental 30 exhaust are to release the pressure at the front end of the cylinder before the piston completes its return stroke, so that said piston will not have a forcible impact at the rear limit of its stroke to decrease the 35 resistance to the advancing piston by increasing the rapidity of exhaust from the front end of the cylinder, also to coöperate with the main exhaust-port in releasing the pressure at the rear end of the cylinder just before the piston reaches the limit of its forward 40 stroke, whereby the piston rebounds freely after its impact, and thus avoids objectionable jarring.

In order to protect the valve against the 45 possibility of impact of the piston, the rear end of the cylinder is closed by a plate or block 60, hereinafter designated a "cushion-plate." This plate consists of an imperforate circular body portion and an annular portion 50 on the rear face of said body portion. The outer diameter of the annular portion is larger than that of the body. The bore of the cylinder is enlarged at the rear end and the annular portion of the plate fits in said bore and abuts against the shoulder formed by such enlargement. In order to admit air from the valve into the cylinder, a slot 61 is cut in the annular portion of said plate in register with a slot or port in the end of the 55 cylinder. This last-mentioned slot communicates with a passage-way 62, extending forwardly in the wall of the cylinder, and opening into said cylinder through a port 63 a sufficient distance from the end thereof to afford 60 a suitable cushion for the piston, as herein-

after described. By this arrangement the air admitted in the rear of said cushion-plate passes through the slot thereof and thence through the passage-way in the cylinder-wall and enters the cylinder near the rear end thereof. In operation the piston upon its return stroke closes the port 63 of the passage-way 62. The air thus confined in the rear end of the cylinder is compressed to a higher degree than the normal or ordinary working 75 pressure and not only constitutes a positive cushion, but initiates the forward movement of the piston and drives it far enough to uncover the admission-port 63.

It is desirable in a riveting-hammer to have 80 a button set incorporated as a part thereof. For this purpose a nosing or sleeve 35 is inserted and rigidly secured in the end of the cylinder. The projecting end of this sleeve is enlarged and has a groove 36 formed in the 85 periphery thereof. In this groove fit the flanges 37 of two semicircular pieces 38, which project beyond the end of the nosing. These pieces 38 are firmly clamped in place by a strong circular spring or resilient split ring 90 39, which rests in grooves 40, provided therefor in the outer surfaces of said pieces, whereby said pieces constitute clamping-jaws for holding the shank of the button set or tool, Figs. 1 and 3. In order to better perform this function, each of the clamping-jaws is provided with a groove 41 on its inner face and the shank of the button set or tool is provided with a rib 42 for interlocking therewith, said 95 rib and grooves being preferably beveled to 100 facilitate insertion and removal of the button set or other tool. The shank of the button set fits in the nosing tight enough to insure the return of the piston, but the rib and grooves are arranged to permit a slight end- 105 wise movement of the shank.

The admission of air is controlled by a throttle-valve in the handle. This valve is a hollow cylindrical cup 43, fitting in a tubular sleeve 44, which is set into a cylindrical bore 110 in said handle. The middle portion of this bore is enlarged to form an annular groove 45 around said sleeve, and the sleeve is provided with a series of perforations 46 in register with said groove. The outer end of said bore is threaded and is closed by a threaded cap 47, fitting thereon and constituting an abutment for a helical spring 48, which rests inside of said sleeve and bears against said cup. The admission-duct 19 extends from 115 a tap at the side of the handle into the groove around said sleeve and from the bottom of the bore to the main-valve admission-port 13. The spring keeps the valve-cup normally 120 in its advanced position, so that its sides close the perforations in the sleeve, and the air is admitted or shut off at the perforations in the sleeve according as the valve-cup is in its 125 backward or advanced position. The movement of the valve-cup is effected by a lever 130

49, mounted on the handle in position to be conveniently manipulated by the thumb of the operator. For this purpose a hole is formed in said handle to admit a short rod 50, which extends from the lever to the cup, whereby the motion of either is transmitted to the other. In order to equalize the pressure on the opposite sides of the valve-cup, a small hole 51 is formed through the end of 10 said cup.

For the sake of clearness, brevity, and convenience of description the foregoing specification assumes that each port and each passage-way have a separate function from the others. In practice, however, it is better to form circumferential grooves in the valve-bushing at the points hereinbefore designated for the several ports and to have a plurality of ports extending through the bushing from 20 the bottom of each groove. This construction not only balances the pressure on the side of the valve and provides a large port area, but also avoids the necessity of having the ports made to register. So, too, instead of 25 single passage-ways above described a plurality of passage-ways may be used for each.

The operation of my hammer is as follows: Upon the manipulation of the lever 49 the throttle-valve in the handle is opened so as 30 to admit live air through the air-supply duct 19. When the valve is in its rearmost position, as shown in Figs. 1 and 12, the air-supply duct 19 communicates with the rear portion of the cylinder through the port 13 in advance of its front end and the passage-way 35 62 around the cushion-plate, and live air is admitted into said cylinder through said port 13 and passage-way 62. In this position of the valve the front end of the cylinder is open to the atmosphere through the port 21 in its end, the passage-way 20, the port 15 in the valve-bushing, the front groove 25 of the valve, and the main exhaust-port 16 in the bushing and exhaust port or ports 24, through 40 the handle-socket to the atmosphere. The front end of the cylinder is also directly open to the atmosphere through the port 55 and passage-way 56. The live air admitted in the rear portion of the cylinder therefore 45 drives the piston forwardly without affecting the position of the valve until it passes and uncovers the port 32. When the port 32 is uncovered, the live air in the rear portion of the cylinder passes therethrough and through 50 the passage-way 31 and the port 12 into the space or chamber in the rear of the valve. As the rear end of the valve is of larger area than the front end and both sides are submitted to direct or cylinder pressure, the valve is 55 driven forwardly to the position illustrated in Fig. 2. This movement of the valve closes the main admission-port 13, and at the same time it opens communication between the main exhaust-port 16 and the port 17, which 60 communicates through the passage-way 22

and port 23 with the rear portion of the cylinder. At the same time the front port 21 of the cylinder and its passage-way 20 are cut off from the main exhaust-port 16 and brought into communication through the 70 front groove 25 of the valve with the small port 14, communicating with the air-supply duct, so that live air is admitted to the front end of the cylinder. By this arrangement the air is cut off from the rear of the piston 75 and admitted to the cylinder in front thereof before it reaches the limit of its stroke. The theory of this arrangement of ports is that by the time the piston is passing the port 32 it has acquired a very rapid speed, and its momentum will carry it a considerable distance before the air admitted through the port 32 shall have had time to effect the movement of the valve, so that the piston will impart its stroke with very little resistance by reason of air being admitted in front of it. In this forward movement of the piston the supplemental exhaust-port 55 serves to increase the rapidity of exhaust from the front end of the cylinder until the piston is nearing the 80 limit of its stroke, and after the rear end of the piston has passed said port 55, said port serves to release the pressure in the rear of said piston, whose motion at this time is continued by its own momentum. When the piston delivers its stroke, there is very little pressure in the rear end of the cylinder to resist its rebound, and at the same time live air is being admitted in the front end of the cylinder to effect the return of the piston. At 85 the beginning of the return stroke of the piston the rear portion of the cylinder is vented through the port 23, passage-way 22, port 17 of the bushing, rear groove 26 of the valve and main exhaust-port 16, and also through 90 the supplemental exhaust-port 55 and passage-way 56. The supplemental exhaust-port 55 is closed near the beginning of the backward stroke; but no effect is produced on the valve until the piston covers the port 23. 95 When, however, the piston covers the port 23, the escape of air from the rear end of the piston-chamber by the exhaust is cut off and the further rearward movement of the piston compresses the air sufficiently to cause it to 100 return the valve to its rearward position, Fig. 12, the pressure passing from the piston-chamber to the front end of the valve-chamber for that purpose through the port 63, passage 62, and port 61. In order to insure the 105 return of the valve at the proper time, the valve may be loosely fitted in the bushing, or a port 64 may be drilled in the bushing from the admission-port through the front end of the bushing, Fig. 10, so as to remain uncovered by the valve at all times. By this arrangement live air is always being admitted in front of said valve without producing any result so long as the exhaust-port 23 is open 110 to the atmosphere; but when the exhaust- 115

65 120 125 130

port 23 is closed by the piston, as in Fig. 12, the live air in the rear of the piston coöperates with the air compressed by the returning piston to force the valve backwardly into its 5 rearward position. When the valve is thus forced back, it is in the position shown in Figs. 1 and 12 and ready to renew the operation hereinbefore described. The piston on its backward stroke passes the port 63, and 10 thereby prevents the admission of air back of the piston; but the initial forward movement of the piston is effected by the expansion of the air confined and compressed in the rear end of the cylinder by the return stroke of the 15 piston.

As hereinbefore suggested, the supplemental exhaust instead of being led rearwardly through the body of the cylinder to the main or regular exhaust 24 may be led directly to 20 the atmosphere by a port or passage extending laterally through the wall of the cylinder, as clearly indicated in Fig. 13, in which such supplemental exhaust-port is shown at 55^a.

What I claim is—

25 1. A pneumatic hammer comprising a cylinder having ports for the admission and escape of air, a piston in said cylinder, and a valve for controlling the admission and release of air, said cylinder having a supplemental exhaust-port located in the forward 30 portion thereof in position to be uncovered by the piston shortly after the initiation of its return movement and before the completion of such return movement, substantially 35 as described.

2. A pneumatic hammer comprising a cylinder having ports for the admission and escape of air, a piston in said cylinder, and a valve for controlling the admission and release of air, said cylinder having a supplemental exhaust-port located in the forward portion thereof in position to be uncovered by the piston shortly after the initiation of its return movement and before the completion 45 of such return movement, said supplemental exhaust-port being permanently open to the atmosphere, substantially as described.

3. A pneumatic hammer comprising a cylinder having ports for the admission and release of air, a piston in said cylinder, a handle portion fastened to said cylinder and having a cylindrical socket-piece closed at one end and nested therein, and a cylindrical valve in said socket-piece in alinement with said cylinder, said valve having grooves in its side to coöperate with the inlet and exhaust ports, substantially as described.

4. A pneumatic hammer comprising a cylinder having ports for the admission and release of air, a piston in said cylinder, a handle portion fastened to said cylinder and having a cylindrical socket-piece closed at one end and nested therein, said cylinder having a reduced end portion fitting within said socket-piece, and a cylindrical valve in said socket-

piece in alinement with said cylinder for controlling the inlet and exhaust ports, substantially as described.

5. A pneumatic hammer comprising a handle portion having ports for the admission 70 and release of air, a cylinder, a piston in said cylinder and an imperforate valve for controlling the admission and release of air, one of said ports being in the rear of said valve and communicating through a passage-way 75 with the middle portion of said cylinder, said valve having two grooves in its side for coöperation with some of said ports, and having its rear end of larger diameter than its front end, substantially as described. 80

6. A pneumatic hammer comprising a cylinder having ports for the admission and release of air, a piston in said cylinder, and a handle clamped to said cylinder and having a cylindrical socket portion, the outer portion 85 of said socket being enlarged and the end of said cylinder being reduced to fit tight therein, and a valve-bushing in the rear portion of said socket provided with ports for the admission and release of air, and a longitudinally-movable valve in said bushing adapted 90 to coöperate with said bushing-ports, substantially as described.

7. A pneumatic hammer comprising a cylinder, a piston therein, a handle having a cylindrical socket portion, a valve-bushing in 95 said socket and a valve in said bushing, the rear end of said valve being enlarged and fitting in the enlarged bore of said bushing, and the front end of said valve fitting loosely in 100 said bushing to permit the leakage of air by said front end, said hammer being provided with ports and passage-ways arranged to be controlled by said valve and said piston, substantially as described. 105

8. A pneumatic hammer comprising a cylinder having ports for the admission and release of air, a piston in said cylinder, and a valve for controlling the admission and release of air, said cylinder having a supplemental exhaust-port located in the forward portion thereof in position to be uncovered by the rear end of the piston shortly before the forward limit of the piston-stroke, and by the front end of the piston soon after the beginning of its rearward stroke, substantially 110 as described. 115

9. A pneumatic hammer comprising a cylinder having ports for the admission and release of air, a piston in said cylinder, and a valve for controlling the admission and release of air, said cylinder having a supplemental exhaust-port located in the forward portion thereof in position to be uncovered by the rear end of the piston shortly before the forward limit of the piston-stroke and by its front end shortly after the beginning of its rearward stroke, said supplemental exhaust-port being permanently open to the atmosphere, substantially as described. 120 125 130

10. A pneumatic hammer comprising a cylinder having ports for the admission and release of air, a piston in said cylinder, and a handle clamped to said cylinder and having a 5 cylindrical socket portion, the outer portion of said socket being enlarged and the end of said cylinder being reduced to fit tight therein, substantially as described.
11. A pneumatic hammer comprising a cylinder having ports for the admission and release of air, a piston in said cylinder, and a handle clamped to said cylinder and having a cylindrical socket portion, the outer portion of said socket being enlarged and the end of 15 said cylinder being reduced to fit tight therein, and a valve-bushing in the rear portion of said socket provided with ports for the admission and release of air, and having its bore enlarged at the rear end, a cylindrical 20 valve in said bushing having a shoulder at its rear end fitting in the enlarged portion of the bushing-bore and having grooves for coöperating with ports in said bushing, one of the ports in said bushing being located at the 25 rear of said valve and communicating through a passage-way in the socket portion and cylinder-wall with a port near the middle portion of the cylinder, substantially as described.
12. A pneumatic hammer comprising a cylinder having ports for the admission and release of air, a piston in said cylinder, and a handle clamped to said cylinder and having a cylindrical socket portion, and a valve-bushing in said socket provided with ports 30 for the admission and release of air and having its bore enlarged at the rear end, a cylindrical valve in said bushing having a shoulder at its rear end fitting in the enlarged portion 35 of the bushing-bore and having grooves for coöperating with ports in said bushing, one of the ports in said bushing being located at the rear of said valve and communicating through a passage-way in said socket portion 40 and cylinder-wall with a port near the middle portion of the cylinder, substantially as described.
13. A pneumatic hammer comprising a cylinder, a piston therein, a handle portion 45 fastened to said cylinder and having a socket constituting a continuation of the cylinder-chamber, a valve-bushing in said socket, and a valve in said bushing, said valve having two circumferential grooves and being enlarged at its rear end, and said hammer having a passage-way extending from the rear of 50 said valve to the middle portion of said cylinder, and a main admission-port in position to be covered by the front end of said valve 55 in its forward position and to be uncovered when the valve is in its rearward position, and a main exhaust-port in position to register with the two grooves alternately, and a 60 passage-way extending from the front end of the cylinder to a port which registers with the front groove of the valve, and a passage-way which extends from the rear portion of the cylinder to a port which registers with the rear groove of the valve, and a supplemental admission-port in position to register 65 with the front groove of the valve when said valve is in its forward position, substantially as described.
14. A pneumatic hammer comprising a cylinder, a piston therein, a handle portion 70 fastened to said cylinder and having a socket portion, a valve-bushing in said socket, and a valve in said bushing, said valve having two circumferential grooves and being enlarged at its rear end, and said hammer having a passage-way extending from the rear of 75 said valve to the middle portion of said cylinder, and a main admission-port in position to be covered by the front end of said valve in its forward position and to be uncovered 80 when the valve is in its rearward position, and a main exhaust-port in position to register with the two grooves alternately, and a passage-way extending from the front end of 85 the cylinder to a port which registers with the front groove of the valve, and a passage-way which extends from the rear portion of the cylinder to a port which registers with the rear groove of the valve and a supplemental admission-port in position to register 90 with the front groove of the valve when said valve is in its forward position, and a supplemental exhaust-port leading from the middle portion of the cylinder to the atmosphere, substantially as described.
15. A long-stroke pneumatic hammer comprising a cylinder having its front end closed with the shank of a tool, and a handle fastened to said cylinder and having a cylindrical socket portion, a bushing in said socket 95 having its bore enlarged at the rear end, a valve enlarged at the rear end and fitting in said bushing, and a piston in said cylinder, said bushing having circumferential grooves in its outer surface and ports extending 100 through said bushing from said groove and arranged to be controlled by said valve, said hammer having passage-ways extending from said groove to the atmosphere and to the front and rear ends of the cylinder, and a 105 passage-way extending from the rear of the valve to the middle portion of the cylinder, substantially as described.
16. A pneumatic hammer comprising a cylinder, a piston therein, a handle fastened 110 to said cylinder in alinement therewith and having a cylindrical socket portion, a bushing in said socket and a valve in said bushing, said bushing having circumferential grooves 115 with ports leading therefrom to the interior of said bushing, the main admission-ports being in position to be covered and uncovered by the front end of said valve, and the rear-most port being at the rear of said valve, and said hammer having passage-ways extending 120

from three intermediate grooves in said bushing to the front and rear ends of the cylinder and to the atmosphere respectively, substantially as described.

17. A pneumatic hammer comprising a cylinder, a piston therein, a handle fastened to said cylinder in alignment therewith and having a cylindrical socket portion, a bushing in said socket and a valve in said bushing, said bushing having circumferential grooves with ports leading therefrom to the interior of said bushing, the main admission ports being in position to be covered and uncovered by the front end of said valve, and the rearmost port being at the rear of said valve, and said hammer having passage-ways extending from three intermediate grooves in said bushing to the front and rear ends of the cylinder and to the atmosphere respectively, substantially as described.

18. A pneumatic hammer comprising a cylinder, a piston therein, a handle having a socket, the outer or forward end of the socket-piece being enlarged and the rearward end of the cylinder being correspondingly reduced to fit into said enlarged end of the socket-piece, a valve-bushing located in the socket-piece and having ports and passages for the admission and exhaust of the motive fluid to and from the cylinder, and a valve arranged in the valve-bushing for governing said ports and passages; substantially as described.

19. A pneumatic hammer comprising a handle portion having ports for the admission and release of air, a cylinder clamped to said handle portion, a piston in said cylinder, and a valve in said handle portion for controlling the admission and release of air, said valve having a groove therein and said handle portion having a small duct inclined forwardly in position to cause the air to impinge against the front wall of said groove, substantially as described.

20. A pneumatic hammer comprising a handle portion having ports for the admission and release of air, a cylinder clamped to said handle portion, a piston in said cylinder, and a valve in said handle portion for controlling the admission and release of air, said valve having a groove therein and said handle portion having a small duct inclined in position to cause the air to impinge against the wall of said groove, substantially as described.

21. A pneumatic hammer comprising a cylinder, a piston therein, ports for the admission and release of air, a valve for controlling the admission and release of air, and a duct leading from the air-supply duct and opening in position and direction to cause the air to impinge against the valve in the general direction of its line of motion, substantially as described.

22. A pneumatic hammer comprising a handle portion having a cylindrical socket, a

socket-piece therein, a bushing in said socket-piece and a valve in said bushing, and a cylinder clamped to said handle portion in alignment therewith, and a piston in said cylinder, said bushing, handle portion and cylinder having continuous passage-ways therethrough for the admission and release of air, and all of said passage-ways being controlled entirely by said valve and piston, substantially as described.

23. A pneumatic hammer comprising a handle portion having ports for the admission and release of air, a cylinder, a piston in said cylinder, and a valve for controlling the admission and release of air, said valve being located back of said cylinder and in alignment therewith, and an imperforate plate in the rear end of said cylinder, substantially as described.

24. A pneumatic hammer comprising a cylinder having ports for the admission and release of air, an imperforate plate at the rear end of said cylinder, a piston in said cylinder, and a handle clamped to said cylinder and having a cylindrical socket portion, a valve-bushing in said socket portion, and a valve in said bushing in alignment with the cylinder, the pressure-admission port extending from the space back of said plate to a point in the piston-chamber sufficiently far from the rear end thereof to constitute an air-cushion therein, substantially as described.

25. A pneumatic hammer comprising a cylinder having passage-ways for the admission and exhaust of pressure, and a valve controlling said passage-ways and constructed to permit leakage of air from the valve-chamber to the rear end of the cylinder; substantially as described.

26. A pneumatic hammer comprising a cylinder having passage-ways for the admission and release of air, and a reciprocating valve for controlling said passage-ways, said hammer having a passage-way extending from the supply-duct to the end of the valve-chamber beyond the range of movement of the valve, substantially as described.

27. The combination, in an impact-tool, of a cylinder, a piston reciprocable therein, inlet and exhaust passages for the motive fluid, and a valve movable in a chamber at one end of the cylinder and serving to control the flow of motive fluid to and from each end of the cylinder, one face of said valve being open to a chamber in which motive fluid is compressed by the piston as the latter approaches one end of its stroke, and the other face of the valve being open to a chamber to which motive fluid under normal pressure is admitted.

28. The combination in an impact-tool, of a cylinder, a piston reciprocable therein, inlet and exhaust passages for the motive fluid, and a valve movable in a chamber at one end of the cylinder and serving to control the flow

of motive fluid to and from each end of the cylinder, said valve having one face open to a chamber in which motive fluid is compressed by the piston as the latter approaches one end of its stroke, and another face of larger area than the first open to a chamber to which motive fluid under normal pressure is admitted.

29. In a pneumatic tool of the type described, a valve to control the admission and exhaust to and from the cylinder, said valve being actuated by direct air-pressure at one stroke of the piston and by compression of the air between it and the piston at the return stroke.

30. The combination in an impact-tool, of a cylinder, a piston reciprocable therein, inlet and exhaust passages for the motive fluid, a valve movable in a chamber at one end of the cylinder and serving to control the flow of motive fluid to and from each end of the cylinder, said valve having an enlarged head, and one face of the valve being open to a chamber in which the motive fluid is compressed by the piston as the latter approaches one end of its stroke, and a passage leading from the chamber which receives the enlarged head of the valve to a point in the cylinder where it will be uncovered by the piston when the latter reaches the forward limit of its stroke, whereby the valve will be moved in one direction by motive fluid compressed by the piston at one end of its stroke, and in the other direction by motive fluid under normal pressure when the piston reaches the other limit of its stroke.

31. In a fluid-pressure-operated tool, the combination with a cylinder, of a reciprocating piston therein, a valve-casing, a differential piston-valve in said casing controlling the supply and exhaust of fluid-pressure to and from the opposite ends of the cylinder, said valve-casing and cylinder having ports and passages whereby the valve is moved in one direction by air compressed by the piston and in the other direction by fluid-pressure flowing through the cylinder from the supply-port.

32. In a pneumatic hammer comprising a cylinder having passage-ways for the admission and release of pressure and a reciprocating valve for controlling said passage-ways, said valve having one end fitting against leakage in the valve-chamber and having its other end arranged to permit a leakage of air into one end of the valve-chamber to insure the movement of said valve, substantially as described.

33. In a pneumatic hammer, a valve to control the admission and exhaust of motive fluid to and from opposite ends of the cylinder, said valve being moved in one direction by air compressed by the piston and in the opposite direction by the motive fluid.

65 34. In a pneumatic hammer, a valve to

control the admission and exhaust of motive fluid to and from opposite ends of the cylinder, said valve being shifted at the forward movement of the piston by motive fluid admitted to one of its pressure areas through a port controlled by the piston, to cause the valve to admit motive fluid in front of the piston to drive the latter rearward, and being shifted in the opposite direction by air compressed by the piston at its backward stroke, to admit motive fluid to the rear end of the cylinder to drive the piston forward again.

75 35. In a pneumatic hammer, a differential valve to control the admission and exhaust of motive fluid to and from the opposite ends of the cylinder, said valve being moved in one direction by air compressed by the piston and in the opposite direction by the motive fluid.

80 36. In a pneumatic hammer, a differential valve to control the admission and exhaust of motive fluid to and from the opposite ends of the cylinder, said valve being moved in one direction by motive fluid admitted to the larger pressure area of the valve at the forward stroke of the piston, and in the opposite direction by air compressed by the piston at its return stroke and acting upon the smaller pressure area of the valve.

85 37. In a pneumatic hammer, a valve to control the admission and exhaust of motive fluid to and from the opposite ends of the cylinder, said valve being located at the rear end of the cylinder and in line therewith and moved in one direction by air compressed by the piston and in the opposite direction by the motive fluid.

90 38. In a pneumatic hammer, a differential valve to control the admission and exhaust of motive fluid to and from the opposite ends of the cylinder, said valve being located at the rear end of the cylinder and in line therewith and moved in one direction by motive fluid admitted to its larger pressure area at the forward stroke of the piston, and in the opposite direction by air compressed by the piston at its return stroke and acting against the smaller pressure area of the valve.

95 39. In a pneumatic hammer, the combination of a cylinder, a piston therein, a valve for controlling the movements of the piston and having one of its pressure areas in communication with the rear end of the piston-chamber, means for admitting motive fluid to the opposite pressure area of the valve, and an exhaust-port for the rear end of the piston-chamber arranged to be closed by the piston during its return stroke to cause the air compressed by the further movement of the piston to shift the valve.

100 40. In a pneumatic hammer, the combination of a cylinder, a piston therein, a differential valve for controlling the movements of the piston, and having its smaller pressure area in communication with the rear end of the piston-chamber.

the piston-chamber, a port and passage leading from the piston-chamber to the larger pressure area of the valve and arranged to be uncovered by the piston at its forward stroke, 5 and an exhaust-port for the rear end of the piston-chamber arranged to be closed by the piston during its return stroke to cause the air compressed by the piston during its further movement to shift the valve.

41. In a pneumatic hammer, a valve to control the admission and exhaust of motive fluid to and from the opposite ends of the cylinder, said valve being shifted in one direction by motive-fluid pressure at the forward 10 movement of the piston and in the opposite direction by air compressed by the piston at its return stroke, and means for permitting a leakage of motive fluid into the rear end of the piston-chamber during the return stroke 15 of the piston.

42. In a pneumatic hammer, the combination of a cylinder, a piston therein, a valve for controlling the movements of the piston and having one of its pressure areas in communication with the rear end of the piston-chamber, a port controlled by the piston for admitting motive fluid to the opposite pressure area of the valve at the forward stroke of the piston, an exhaust-port for the rear end 25 of the piston-chamber arranged to be closed by the piston during its return stroke, and means for permitting a leakage of motive fluid into the rear end of the piston-chamber during the return stroke of the piston.

43. In a pneumatic hammer, the combination of a cylinder, a piston therein, a differential valve for controlling the movements of the piston and having one of its pressure areas in communication with the rear end of 30 the piston-chamber, means for admitting motive fluid to its opposite pressure area, an exhaust-port for the rear end of the piston-chamber arranged to be closed by the piston during its return stroke, and means for permitting leakage of motive fluid into the rear 35 end of the piston-chamber during the return stroke of the piston.

44. In a pneumatic hammer, the combination of a cylinder, a piston therein, a differential valve for controlling the movements of the piston and having its smaller pressure area in communication with the rear end of the piston-chamber, a port and passage leading from the piston-chamber to the larger pressure 40 area of the valve and arranged to be uncovered by the piston at its forward stroke, an exhaust-port for the rear end of the piston-chamber arranged to be closed by the piston during its return stroke, and means for permitting a leakage of motive fluid into the rear 45 end of the piston-chamber during the return stroke of the piston.

45. In a pneumatic hammer, the combination of a cylinder, a piston of uniform diameter therein, a valve for controlling the admission

and exhaust of motive fluid to and from the opposite ends of the cylinder, and a passage leading from one pressure area of the valve to the piston-chamber and opening into the latter by a port uncovered by the rear end of the piston at the forward stroke of the latter, to admit motive fluid from the piston-chamber to said pressure area of the valve, and uncovered by the front end of the piston at the rearward stroke of the latter to permit said motive fluid to exhaust into the front end of the piston-chamber.

46. In a pneumatic hammer, the combination of a cylinder, a piston therein, a valve block or bushing at the rear end of the cylinder provided with a series of ports and passages communicating with the motive-fluid supply, the front end of the cylinder, the atmosphere, and the rear end of the cylinder, respectively, and a valve operating in said valve block or bushing and having along its length two grooves or recesses for governing said series of ports, said valve having one end exposed to the rear end of the piston-chamber and its other end in communication with the piston-chamber through a port controlled by the piston.

47. In a pneumatic hammer, the combination of a cylinder having a piston-chamber and ports for the admission and exhaust of the motive fluid, means for closing the rear end of the chamber to form an air-cushion therein, a valve for controlling said ports and arranged in rear of the piston-chamber, the inlet-port opening into the piston-chamber 100 at a point forward of the rear end thereof so as to form an air-cushion therein, and a piston operating to close said inlet-port on its rearward stroke and be cushioned by the air trapped in the rear end of the piston-chamber.

48. A pneumatic hammer having a cylinder with ports and passages for the admission and exhaust of motive fluid to and from its opposite ends, and a permanently-open supplemental exhaust-port located intermediate the length of the cylinder in position to be uncovered by the rear end of the piston shortly before the forward end of the piston-stroke, to thereby exhaust the motive fluid behind the piston, and to be uncovered by the front end of the piston shortly after the initiation of the return piston-stroke, to thereby exhaust the motive fluid in front of the piston.

49. A pneumatic hammer having a cylinder with ports and passages for the admission and exhaust of motive fluid to and from its opposite ends, and a supplemental exhaust port and passage controlled by the piston and arranged to exhaust the cylinder on opposite sides of the piston, said supplemental passage extending from the piston-chamber rearwardly and longitudinally through the cylinder-wall to the main or regular exhaust-port adjacent the rear end of the hammer.

50. A pneumatic hammer having a cylinder with ports and passages for the admission and exhaust of motive fluid to and from its opposite ends, a valve for controlling said ports and passages, and means for exhausting the front end of the cylinder independently of the valve before the piston approaches the rear end of its stroke.

51. A pneumatic hammer having a cylinder with ports and passages for the admission and exhaust of motive fluid to and from its opposite ends, a valve for controlling said ports and passages, and means independent of the valve for exhausting the cylinder on opposite sides of the piston at the rear end of its forward stroke and near the beginning of its rearward stroke.

52. A pneumatic hammer having a cylinder with ports and passages for the admission and exhaust of motive fluid to and from its opposite ends, a valve controlling said ports and passages and moved in one direction by air compressed by the piston and in the other direction by motive fluid controlled by the piston, and means for exhausting the front end of the cylinder independently of said valve.

53. A pneumatic hammer having a cylinder with ports and passages for the admission and exhaust of motive fluid to and from its opposite ends, a valve controlling said ports and passages and moved in one direction by air compressed by the piston and in the other direction by motive fluid controlled by the piston, and means independent of the valve for exhausting the cylinder on opposite sides of the piston.

54. A pneumatic hammer having a cylinder with ports and passages for the admission and exhaust of motive fluid to and from its opposite ends, and a valve controlling said ports and passages and constructed to permit leakage of motive fluid to the rear end of the cylinder when in position to otherwise cut off the supply of motive fluid thereto.

55. A pneumatic hammer having a cylinder with ports and passages for the admission and exhaust of motive fluid to and from its opposite ends, and a valve controlling said ports and passages and having at its front end a piston-head governing the admission of the motive fluid to the rear end of the cylinder, said piston-head being arranged to permit leakage of the motive fluid to the rear end of the cylinder when the valve is in position to otherwise cut off the supply of motive fluid thereto.

56. In a pneumatic hammer, the combination of a cylinder, a valve-bushing having ports and passages for the admission and exhaust of motive fluid to and from the cylinder, said bushing having a circumferential groove located adjacent the rear end of the cylinder and containing a constant supply of motive fluid, a valve operating in said bushing and controlling said ports and passages, and a constantly open but restricted passage between said groove and the rear end of the cylinder.
